By T. M. D. G. G.*

UNITED STATES PATENT OFFICE.

JACOB W. DIEPHOUSE, OF CHICAGO, ILLINOIS.

VACUUM-CLEANER.

1,396,263.

Specification of Letters Patent.

Patented Nov. 8, 1921.

Application filed September 12, 1917. Serial No. 190,893.

To all whom it may concern:

Be it known that I, JACOB W. DIEPHOUSE, a citizen of the United States, residing at Chicago, in the county of Cook and State 5 of Illinois, have invented certain new and useful Improvements in Vacuum-Cleaners, of which the following is a specification.

This invention relates to vacuum cleaners and has for its object to provide a machine 10 of this character adapted to be operated by hand, simple in construction, light in weight and which can be manufactured at comparatively low cost.

In the accompanying drawings, illustrating the invention,

Figure 1 is a sectional elevation of the machine;

Fig. 2 is a front view of the vacuum and 20 sweeper casings;

Fig. 3 is a sectional view on the line 3—3 of Fig. 1, and

Fig. 4 is a fragmentary view on a smaller scale.

Referring to the drawing, a sweeper casing 4 is fastened by one or more screws 5 to the underside of a vacuum casing 6. The sweeper casing may be made in any suitable size and shape and it is mounted to travel on two rollers 7 at the front of the casing and 25 two wheels 8 at the rear of the casing, the latter wheels having rubber tires 9 which travel in contact with the rollers 10 on the ends of the revolving sweeper 11. The rollers, wheels and sweeper are of any suitable 30 form and construction and are mounted in the ends of the sweeper casing in an approved manner. A dust trough 12 is pivotally mounted at 13 within the sweeper casing in front of the sweeper and is normally 35 held in elevated position by a spring 14. A lever 15 is engaged with the trough and projects outward through the sweeper casing so that it can be manipulated by hand or foot to depress the trough against the 40 tension of its spring to clean the trough. Another dust trough 16 is pivoted at 17 in the ends of the sweeper casing behind the sweeper, and this trough is likewise held in elevated position by a spring 17' and is provided with a lever 18 which projects outward 45 through the casing in convenient position for manipulation by the hand or foot to depress the trough for cleaning.

The vacuum casing is made to fit snugly 50 over the front and top of the sweeper casing and is provided with an elongated mouth 19

which is located slightly below the lower edge of the sweeper casing and in front of the dust troughs and sweeper. The vacuum casing tapers upwardly and rearwardly to 60 its rear end which is shaped to form the fan casing 20 arranged in upright position immediately above the sweeper casing. This fan casing is shown to be an integral part of the vacuum casing and is so preferably 65 made, but these two casings may be made in separate parts and properly secured together. The casing is provided with an outlet nozzle 21 to which a dust collecting bag may be attached in any desired manner. A 70 fan 22 of suitable construction is mounted within the fan casing upon a shaft 23 journaled in a bearing 24 on the back of said casing. The shaft 23 carries a pinion 25 which meshes with a gear 26 on another 75 shaft 27 journaled in a bearing 28 on the back of the front casing and this shaft 27 also carries a pinion 29 which meshes with a gear 30 mounted on the drive shaft 31 which is supported in bearings 32 in a gear 80 box 33 secured on the back of the fan casing. The drive shaft is provided with a universal joint 34 of any suitable kind within the gear box and adjacent to the bearings 32 and the shaft projects outward through a slot 35 in 85 the rear end of the gear box. The upper end of the shaft carries a bevel pinion 36 which meshes with a bevel gear 37 mounted in bearings in a box 38 and operated by a crank 39. The box 38 is mounted on a tube 90 40 in which the drive shaft operates and a handle 41 is fastened to the box. The tube 40 is provided at its lower end with a fork 42 which embraces the gear box 33 at its rear end, and the ends of the fork are piv- 95 otally engaged at 43 with the gear box. To provide for longitudinal expansion of the shaft 31 when the shaft is swung vertically and insure proper meshing of the gears 36 and 37 I divide the shaft into two parts and 100 connect them by a slip joint consisting of a sleeve 44 fastened at one end to one part as 31' of the shaft and loosely receiving the end of the other part as 31" which is provided with a transverse pin 45 operating 105 through slots 46 in the sleeve. Since the shaft and the tube are pivoted at different centers it will be readily understood that as the handle 41 is raised or lowered the shaft 31 will adjust itself longitudinally as re- 110 quired.

A trailer wheel 47 is mounted on a bracket

- 48 beneath the gear box 33 primarily to prevent the machine from tilting when it is drawn backward but also to facilitate the movement of the machine in use.
- 5 My invention provides a compact and simple machine of this character which is very light in construction, easy to operate and which will perform its work in a thorough and efficient manner. I am aware that 10 changes in the form and proportion of parts may be made without departing from the spirit or the scope of the invention and I, therefore, reserve the right to make all such changes as fairly fall within the scope of 15 the following claims.
- I claim:
1. In a vacuum cleaner, the combination of a vacuum casing, a nozzle in proximity to the surface to be cleaned and in communication with said vacuum casing, a fan casing, a fan in said fan casing, a gear box mounted on said fan casing, gearing in said gear box for operating said fan, a tube pivotally mounted at one end on said gear box, and 25 carrying another gear box on its outer end, a shaft engaging with said gearing to operate the same and projecting outwardly through the rear end of the first mentioned gear box and into said last mentioned gear 30 box, a universal joint on said shaft within the first mentioned gear box, and means carried by said last mentioned gear box for op-
  - erating said shaft, said shaft being in two parts and its ends being connected by a slip joint within said tube. 35
  2. In a vacuum cleaner, the combination of a vacuum casing, a nozzle in proximity to the surface to be cleaned and in communication with said vacuum casing, a fan casing, a fan in said fan casing, a gear box 40 mounted on said fan casing, gearing in said gear box for operating said fan, a tube pivotally mounted at one end on said gear box, another gear box mounted on the other end of said tube, a shaft engaged with said gearing to operate the same and projecting outwardly through the rear end of the first mentioned gear box and into the last mentioned gear box, a universal joint on said shaft within said first mentioned gear box, 45 bevel gears within said last mentioned gear box for operating said shaft, a crank for operating said bevel gears, said shaft being in two parts within said tube, a sleeve inclosing the adjacent ends of said parts, said sleeve 50 being fastened to one end and loosely receiving the other end and having a slot between its ends, and a pin on the loosely received end of the shaft projecting into said slot. 55

JACOB W. DIEPHOUSE.
